Primary Examiner — Kevin Rudzinski(74) *Attorney, Agent, or Firm* — Lowenstein Sandler LLP(57) **CLAIM**

The ornamental design for a portion of a display panel with a graphical user interface, as shown and described.

DESCRIPTION

The FIGURE is a front view of a portion of a display panel with a graphical user interface showing our new design. The broken lines showing of a portion of a display panel of a communications terminal and portions of the graphical user interface are included for the purpose of illustrating environmental structure and form no part of the claimed design.
